CLAIM

The ornamental design for a multi-camera imaging system as shown and described.

DESCRIPTION

This invention was made with U.S. Government support under grant number 2136737 awarded by the National Science Foundation. The Government has certain rights to this invention.

FIG. 1 is a top, rear, and left side perspective view of a multi-camera imaging system;

FIG. 2 is a bottom, front, and right side perspective view thereof;

FIG. 3 is a top view thereof;

FIG. 4 is a bottom view thereof;

FIG. 5 is a left side view thereof;

FIG. 6 is a right side view thereof;

FIG. 7 is a front plan view thereof;

FIG. 8 is a rear plan view thereof; and,

FIG. 9 is a top, front, and left side perspective view thereof, shown in condition of use with an exemplary unattended vehicle disclosed in broken lines to illustrate an environment.

The broken lines depict portions of the multi-camera imaging system that form no part of the claimed design. The broken lines showing an exemplary unattended vehicle in FIG. 9 represent environmental structure in which the multi-camera imaging system may be used that forms no part of the claimed design.
